J. KERNES

PORTABLE ELECTRIC LAMP

Filed Nov. 8, 1926

Inventor:
James Kernes,
By Harvey L. Hanson
Attorney.

UNITED STATES PATENT OFFICE.

JAMES KERNES, OF CHICAGO, ILLINOIS, ASSIGNOR TO KERNES MANUFACTURING CO., OF CHICAGO, ILLINOIS, A CORPORATION OF ILLINOIS.

PORTABLE ELECTRIC LAMP.

Application filed November 8, 1926. Serial No. 146,927.

The invention relates to a portable electric lamp, and particularly a portable electric lamp stand, in which the lamp and its shade and the exterior shade may be simultaneously or independently moved to any desired angle in order to cause the rays of light from the lamp to project in the direction desired.

One of the objects of the invention is to construct the lamp with an upright standard and supply various parts and members which will permit the ready and accurate adjustment of the lamp bulb so that the rays therefrom will project in varied directions, the adjustment being such that the lamp may be rotated backwardly or forwardly in complete circles of 360° and held in the position desired, so that, in other words, the light rays may be directed upwardly or downwardly, or to either side of the lamp stand.

Another object of the invention is to construct the lamp stand with an attached shade holder for holding and carrying an exterior shade, which shade may be rotated and also tilted to any angle desired.

At the present time certain forms of portable electric lamps, called bridge lamps, are constructed with a floor base, a relatively long vertical standard, and a straight or curved extension, or a movable and adjustable lateral bracket, ending in the socket with its electric lamp bulb and shade. Electric wires are concealed in the base, pedestal or support, and the extension or bracket. The invention overcomes various objections to these forms of bridge lamps in providing a unitary combined lamp and shade holder, avoiding the unwieldiness and the unbalanced effect of the bridge lamps referred to without sacrificing the desirable function of causing the light rays from the lamp to be projected to the table, reading matter, or other object, as may be desired.

It is a further object of the invention to enable the lamp and shade to be rotated or tilted in the directions desired with the least difficulty, and for this purpose ball and socket joints are used in the lamp stand.

Because of the particular construction of the standard, and the curved cross-arm in the looped support of the standard, even when the interior and exterior shades are tilted, balancing of the structure is secured, thus enabling the portable lamp to be easily

transported from place to place, and to maintain its equilibrium.

The invention has the above and other objects, all of which will be explained and more thoroughly understood when read in conjunction with the accompanying drawings which illustrate an embodiment of the invention, it being obvious that changes and modifications thereof may be made without departing from the spirit of the appended claims forming a part hereof.

In the drawings:

Figure 1 is an elevational view of the portable electric lamp embodying the invention.

Figure 2 is a view partly in elevation and partly in section, showing a portion of the standard, the lamp support, the curved cross-arm, and the adjustable interior and exterior shades.

Figure 3 is a side view of the lamp support and interior shade showing the cross-arm of the lamp support and interior shade in full and also dotted lines, and showing the exterior shade in section, and tilted to one side.

Figure 4 is a cross sectional view of the ball and socket joint employed in connection with the exterior shade, and,

Figure 5 is a sectional view of a portion of the cross-arm, lamp support and intervening ball and socket joint.

In the portable electric lamp structure shown in the drawings the vertical standard 10, which may be of wood, metal or any other suitable material, is provided with the base 11, which is sufficiently large and broad to give ample support and to cause the lamp structure to remain in a steady position. The standard and the base are bored and apertured for the admission of electric light wires.

It will be understood that the invention is not limited to a stand lamp having a relatively long upright standard and a base, but, with suitable changes, it may be employed as a table or desk lamp, and could also be made in other forms.

Secured in the top of the upright standard 10 is the elliptical or looped combined lamp and shade support 12 formed from suitable sized metallic tubing. The combined lamp and shade support 12 is secured to the standard 10 in any approved manner,

as by having a hollow bushing or extension screw-threaded into the top of the standard 10. The joint between the lamp support 12 and the standard 10 is covered by the 5 apertured junction portion 13. This junction portion may be of any suitable size or shape, and may be plain or ornamental, as desired.

A cross-arm 14, preferably made of two 10 sections of curved metallic tubing, is disposed preferably centrally between the two sides of the lamp support 12. The curved tubular cross-arm 14 is rotatably and removably secured to the lamp support 12 by 15 the two ball and socket joints. Each of the ball and socket joints comprises the hollow apertured ball member 15, secured in the ends of the cross-arm tube 14, the exteriorly threaded socket member 16, permanently secured to the inner respective side of the lamp support 12, and the interiorly threaded thimble 17 which connects the ball 15 with the socket 16. The ball and socket joints are at the outer ends of the cross-arm 14. 20 25 The connecting thimble 17 is provided with an exterior knurling 18.

The other or inner ends of the tubular cross-arm 14 are permanently secured, as by welding, to opposite sides of a metallic electric light socket and shade holder 19. The holder 19 is dished or hollow substantially semi-spheroidal, and is provided with the base portion 20. The metallic dished holder is provided with the plurality of shade 30 35 holder screws 21 to hold the interior lamp shade 22 in place in the metallic dished holder 19. An electric bulb or lamp socket 23 is secured to the metallic base 20 of the dished member 19 in the interior thereof in 40 any approved manner, as by soldering or welding. The electric light bulb or lamp 24 is screwed into place in the socket 23. The lamp chain 25 extends from the lamp socket 23 through the shade holder 19 and hangs 45 down on the exterior of the shade holder 19, where it may be readily used to operate the electric light bulb 24.

While it is preferred to use a single socket and a single electric light bulb in the interior of the metallic socket and shade holder 19 so that in conjunction with the interior lamp shade 22 direct light rays may be secured without the cross beams of light if more than one lamp bulb should be used, 50 55 yet it will be obvious that, if desired, a plurality of electric light bulbs may be used within the holder 19, and it will also be obvious that interior light shades of different shapes or contours may be used.

60 Electric wires 26 and 27 extend through the base 11 and the upright standard 10 through the junction portion 13, the lower portion of either arm of the lamp support 12, through the respective ball and socket joint, through the respective branch of the

curved cross-arm 14 into the holder 19, and are connected to the lamp socket 23 in the ordinary manner. The wires 26 and 27 are entirely concealed within the structure.

The wires 26 and 27 are preferably placed 70 in the standard, lamp and shade support, cross-arm and shade holder loosely enough so that they may be twisted and untwisted backwardly and forwardly, as desired, when the cross-arm 14, the shade holder 19 with 75 the interior shade 22 and the socket and lamp 23 and 24 respectively, are rotated by means of the ball and socket joints in the cross-arm. It will thus be readily seen that the cross-arm 14 carrying the shade holder, 80 lamp and interior shade may be rotated backwardly and forwardly in complete circles of 360°, and may be secured at any point in the cycle of rotation by means of the friction fit between the members of the 85 ball and socket joints in the cross-arm.

In the looped lamp support the ball and socket with the connecting thimble must, in each case, be of sufficient strength to withstand the strains placed upon them when 90 the cross-arm, the combined shade and socket holder, and the interior shade are shifted out of vertical alignment. The strain is reduced to some extent because of the balancing of the shade holder and shade, 95 secured because of the curve in the cross-arm and the consequent positioning of the shade holder and the interior shade. The whole lamp stand is balanced because of the balancing of the shade holder and shade in 100 the curved cross-arm when the shade holder and shade have been turned or shifted out of vertical alignment.

The dotted line 28 shown in Figure 3 is to indicate that the lamp bulb and shade 24 105 and 22 respectively make a complete revolution of 360° in either direction when the cross-arm 14 is rotated in the ball and socket joints.

It will also be understood, of course, that 110 the electric light wires 26 and 27 may be extended through either arm of the lamp support 12 and the corresponding branch of the cross-arm 14.

The elliptical or looped lamp support 12 115 may be constructed with other forms of support, such as rectangular, triangular or otherwise, but it must be adapted to be constructed with a cross-arm which extends from one side to the other of the lamp support.

The looped lamp support 12 is provided at its top with the lamp shade supporting post 29, to which the exterior lamp shade 30 is secured. The lamp shade 30, the lower 120 edge of which is preferably hung below the lower end of the interior lamp shade 22, is secured by a plurality of cross braces 31 to the lamp shade post 29, which is suitably secured in the top of the lamp support 12. 125 130

The plurality of cross braces 31 are secured at their outer ends to the shade 30 in any well known manner. They are secured at their inner ends to a ring 32, which may 5 rotate about the lamp shade post 29.

The exterior shade post 29 includes a ball and socket joint comprising the ball member 33, the socket member 34, and the connector thimble 35 with the knurling 36. A 10 screw-threaded thimble 37 is shown in Figure 4, which may be used for the purpose of securing the lamp shade post 29 in the top of the lamp support 12.

The lamp shade 30 may be rotated in the 15 ball and socket joint in the lamp shade post 29, and, because of the friction fit between the members of the ball and socket joint in the post 29, the shade may also be tilted to any position required. It will be apparent 20 that not only may the interior shade 22 and the light bulb and socket be set at any position desired, but, simultaneously, the shade 30 may be tilted and set at any position desired, so that the rays of light 25 from the lamp 24 may be made to project to any place desired. It will also be seen that there may be cooperative relationship between the setting of the interior and exterior shades to secure a proper projection 30 of the light rays from the lamp, although they operate separately.

The interior of the shade holder 19 may be provided with reflecting material so that the rays of light emanating from the lamp 35 bulb 24 may be reflected thereby, and it will also be apparent that the top of the lamp shade post 29 may be of any ornamental and artistic design.

Having thus described the invention, what 40 I claim and desire to secure by Letters Patent is:

1. In a portable electric lamp the combination of a hollow standard, a stationary tubular looped lamp support, a tubular curved 45 cross-arm extending across said looped lamp support, said cross-arm having a centrally disposed dished member within which is secured a lamp socket, said cross-arm having a ball and socket joint near each of its ends 50 between said centrally disposed dished member and the respective sides of the tubular loop, said socket having an exterior thread, a thimble with an interior thread, said thimble being screw-threaded on said socket 55 whereby said cross-arm and centrally disposed dished member may be set at any position within 360° of rotation of said cross-arm, dished member, and lamp socket within said loop, said hollow standard, tubular 60 loop, tubular curved cross-arm and centrally disposed dished member furnishing a continuous passage for wiring to said lamp socket.

2. In a portable electric lamp the combination of a hollow standard, a tubular

looped lamp support, a tubular curved cross-arm extending across said looped lamp support, said cross-arm having a centrally disposed dished member within which is secured a lamp socket, said cross-arm having 70 a ball and socket joint near each of its ends between said centrally disposed dished member and the respective sides of the tubular loop, said socket having an exterior thread, a thimble with an interior thread, said thimble being screw-threaded on said socket whereby said cross-arm and centrally disposed dished member may be set at any 75 position within 360° of rotation of said cross-arm, dished member, and lamp socket within 80 said loop, said hollow standard, tubular loop, tubular curved cross-arm and centrally disposed dished member furnishing a continuous passage for wiring to said lamp socket, a lamp bulb fitted in said socket, an interior 85 lamp shade fitted within said dished member, a post secured to the top of said looped member, said post comprising a ball and socket joint, and a holder for an exterior lamp shade, said ball and socket joint in 90 said post permitting the tilting of the exterior shade held by said shade holder.

3. In a portable electric lamp the combination of a hollow standard, a tubular looped lamp support, a tubular curved cross-arm 95 extending across said looped lamp support, said cross-arm having a centrally disposed dished member within which is secured a lamp socket, said cross-arm having a ball and socket joint near each of its ends between said centrally disposed dished member and the respective sides of the tubular loop, said socket having an exterior thread, a thimble with an interior thread, said thimble being screw-threaded on said socket 100 whereby said cross-arm and centrally disposed dished member may be tilted or set at any position within 360° of rotation of said cross-arm, dished member, and lamp socket within said loop, said hollow standard, tubular loop, tubular curved cross-arm and centrally disposed dished member furnishing a continuous passage for wiring to 105 said lamp socket, a lamp bulb fitted in said socket, an interior lamp shade fitted within 110 said dished member, a post secured to the top of said looped member, said post comprising a ball and socket joint, and a holder for an exterior lamp shade, said ball and socket joint in said post permitting the tilting of the exterior shade held by said shade holder simultaneously with the tilting or setting in position of said cross-arm, dished member and lamp socket, said holder for 115 said exterior shade being rotatable on said 120 post.

4. In a portable electric lamp the combination of a standard terminating in a loop, a cross-arm extending across said loop, said cross-arm being curved and having a dished

4

or cupped member, a lamp socket contained in said dished member, said dished member being adapted to carry an interior shade, said cross-arm carrying the dished member and socket in the curved portion of said cross-arm whereby balance of the portable electric lamp is secured when said cross-arm, dished member and interior shade are out of vertical alignment with said standard and 10 said loop, said cross-arm, dished member and lamp socket being rotatable within said loop, a post secured to the top of said looped member, said post comprising a ball and socket joint, and a holder for an exterior 15 lamp shade, said ball and socket joint in said post permitting the tilting of the exterior shade held by said shade holder.

5. In a portable electric lamp, the combination of a hollow standard, a stationary, tubular, looped lamp support, a tubular curved cross-arm extending across said looped lamp support, said cross-arm having a centrally

disposed dished member within which is secured a lamp socket, said dished member being adapted to carry a shade, said cross-arm 25 having a ball and socket joint near each of its ends between said centrally disposed dished member and the respective sides of the tubular loop whereby said cross-arm and centrally disposed dished member may 30 be set at any position within 360° of rotation of said cross-arm, and whereby balance of the portable electric lamp is secured when said cross-arm, dished member and shade are out of vertical alignment with said loop, 35 said hollow standard, tubular loop, tubular curved cross-arm and dished member furnishing a continuous passage for wiring to said lamp socket.

In witness whereof, I hereunto subscribe 40 my name this 3rd day of November, A. D., 1926.

JAMES KERNES.
